COMBINED SOLDERING IRON AND STAND

Richard O. Spencer, South Laguna, Calif., assignor to
Eldon Industries, Inc., Hawthorne, Calif.

Filed Dec. 19, 1974, Ser. No. 534,362

Term of patent 14 years

Int. Cl. D8—05

U.S. Cl. D8—71

FIG. 1.

FIG. 3.

FIG. 2.

FIG. 4.

FIG. 5.

FIG. 6.

FIG. 1 is an isometric view of a combined soldering iron and stand embodying the new design of my invention;

FIG. 2 is a side elevational view of the right side thereof;

FIG. 3 is a rear elevational view thereof;

FIG. 4 is a front elevational view thereof;

FIG. 5 is a top plan thereof; and

FIG. 6 is a bottom plan view thereof.

The cord which is shown broken off in various figures of the drawing is a conventional electric cord connecting the combined soldering iron and the stand.

I claim:

The ornamental design for a combined soldering iron and stand, substantially as shown and described.
